United States Patent Office

Des. 180,686
Patented July 23, 1957

180,686

BUILDING

James C. Everett, Orlando, Fla.

Application June 14, 1956, Serial No. 41,894

Term of patent 7 years

(Cl. D13—1)

Fig. 1.

Fig. 2.

Fig. 1 is an elevational view of one side of a building showing my new design, the appearance of the four sides of the building being identical.

Fig. 2 is a top plan view of the building.

I claim:

The ornamental design for a building, as shown.
